STOCK AND DIE LUBRICATOR

Jesse R. Haeffner, Leavenworth, Kans.

Application April 2, 1941, Serial No. 386,524

5 Claims. (Cl. 10—126)

This invention relates to lubricating devices and more particularly to stock and die lubricators.

At the present time in the use of pipe threading stocks and dies, and cutters of the hand operated type in the operation of cutting the thread or pipe, it is the practice for the operator to periodically stop and oil the pipe and dies with a common oil can in order to assist in the cutting of the threads and to provide a smooth thread. It is an object of this invention to provide an automatically operable oiling means for the dies, cutters and the pipe which will periodically oil the pipe between the dies or the cutters as the device is rotated during the thread or pipe cutting operation so as to thereby eliminate the necessity of stopping the die or cutter structure and manually oiling the work.

Another object of the invention is to provide a lubricator of this kind which may be formed in one or more of the handles of the stock and which will forcibly eject a small quantity of lubricant or cutting fluid onto the work as the threading or cutting operation progresses.

A further object of this invention is to provide a lubricator of this kind wherein the lubricator is set in operation upon raising one of the operating handles for the stock, the oil ejecting means operating by gravity to forcibly eject a small quantity of lubricant or cutting fluid onto the work during each revolution of the device.

A further object of this invention is to provide a device of this kind wherein one or more of the handles for the stock constitutes a lubricant reservoir in addition to a lubricant or cutting fluid ejector which is normally in closed position, but which is adapted to eject or pump a small quantity of liquid onto the work as the threading operation progresses.

Embodying the aims aforesaid and others which may hereinafter appear, the invention consists of the novel construction, combination and arrangement of parts as will be more specifically referred to and illustrated in the accompanying drawing, wherein are shown embodiments of the invention, but it is to be understood that changes, variations and modifications may be resorted to which fall within the scope of the invention as claimed.

In the drawing:

Figure 1 is a longitudinal section, partly broken away, and in detail, of a thread cutting stock and die having a lubricator constructed according to an embodiment of this invention formed in one of the stock handles;

Figure 2 is an enlarged fragmentary sectional view taken on the line 2—2 of Figure 1;

Figure 3 is a sectional view taken on the line 3—3 of Figure 1;

Figure 4 is a bottom plan view of the lubricator removed from the stock;

Figure 5 is a detail side elevational view of the fluid ejector or plunger; and

Figure 6 is a sectional view taken on the line 6—6 of Figure 1.

Referring to the drawing the numeral 10 designates generally a die stock within which a pair of thread cutting dies 11 are adapted to be positioned. The dies 11 are adapted to cut peripheral threads in a pipe or rod 12 which engages the two dies. The stock 10 is of conventional construction and is provided with a pair of diametrically opposed tubular handles 13 and 14. At the present time, in the use of the stock 10 it

20 is the practice, at substantially each complete revolution of the stock, for the operator to apply a small quantity of lubricant or cutting fluid onto the periphery of the pipe 12 so as to assist in cleanly cutting of the threads by the dies 11.

25 In order to provide a means whereby the cutting fluid or lubricant may be automatically ejected onto the work 12 as the dies 11 progress along the length of the work 12, the tubular handle 14 is constructed in the form of a fluid reservoir being provided at its outer end with a plug

30 15 having a gasket 16 interposed between the outer portion of the plug 15 and the outer end of the reservoir or tubular handle 14. The reservoir 14 is adapted to be substantially filled with

35 a lubricant or cutting fluid and in order to provide means whereby this fluid may be periodically and forcibly ejected through the stock 10 and between the two dies 11 onto the periphery of the work 12, I have provided a fluid ejecting

40 means, generally designated as 17, which is mounted in the inner end of the reservoir 14. The reservoir 14 is provided with peripheral threads 18 at its inner end which are threaded into a threaded opening 19 formed in the stock

45 10.

The fluid ejecting means 17 comprises a body 20 which is threaded as at 21 into the inner end of the reservoir 14. The body 20 is formed with an axial bore or cylinder 22 which opens upwardly into the interior of the reservoir 14. The reduced diameter guide sleeve 23 extends inwardly from the body 20 and provides a guide means

50 for a fluid ejecting plunger or piston 24 which is slidably in the guide 23 and in the bore 22. The plunger or piston 24 is formed of a cylin-

55 der.

drical rod which has a longitudinally extending cut-out 25 in one side thereof within which the set screw or plunger limiting member 26 is adapted to loosely engage. The limiting member 26 is formed of a small screw which is threaded into the body 20 and which has the head thereof counter-sunk in a recess 27 formed in the body 20. The plunger 24 is also provided in the periphery thereof with a longitudinally extending flat face 28 which extends from opposite ends of the cutout 25 and which forms a fluid passage so that the fluid from the reservoir 14 may readily flow through the guide 23 into the cutout 25 and then past the lower portion of the flat portion 28 into the fluid ejecting chamber 29 which is formed as a part of the member 20 below the inner end of the plunger or piston 24. The inner end of the plunger or piston 24 is provided with an enlarged flat head 30 and a plunger retracting spring 31 engages about the plunger 24 and about the guide 23, the spring 31 bearing, at its inner end, against the head 30 and at the opposite end against the inner end of the body 20.

The body 20, inwardly from the fluid ejecting chamber 29, is provided with a reduced bore 32 and a spring pressed conical valve 33 is adapted to normally seat against the inner end of the reduced bore 32 as at 34. The valve member 32 is slideable in a bushing 35 which is threaded as at 36 in the inner end of the body 20 and the bushing 35 is formed with an enlarged chamber 37 within which the conical valve member 33 loosely engages. The valve member 33 is provided with an axial stem 38 which is slideable in a reduced bore 39 formed in the bushing 35 and a substantially light spring 40 is mounted in the reduced bore 39 and bears at its inner end against the valve head 33 so as to constantly urge the valve head or member 33 to a closed position on the seat 34. The bushing 35, at its lower end, is formed with a nut head 41 which engages in an annular recess 42 formed in the outer or lower end of the body 20. The nut member 41 is provided with a fluid passage 43 which is co-axial with the bore 39 and preferably a reduced fluid passage 44 is formed between the outer end of the bore 39 and the inner end of the bore 43. A tubular fluid conducting member 45 is fixed in any suitable manner to the bushing 35, being soldered or welded to the nut member 41 and this fluid conducting pipe or member 45 is adapted to extend through an opening 46 formed in the stock 10 so that the free end of the pipe or fluid conducting member 45 is disposed in a position adjacent the work 12 and between the two die members 11.

In order to provide a means whereby the plunger 24 may be periodically and automatically operated to a fluid ejecting position upon rotation of the stock 10, I have provided a plunger operating member, generally designated as 46, which is slideable within the reservoir 14. The plunger operating member 46 is constructed in the form of an elongated round rod 47 having a reduced or conical lower end 48 which is adapted to impact against the head 30. The rod 47 is substantially shorter in length than the length of the reservoir 14 so that when the reservoir 14 is in a vertical position the rod 47 will gravitatingly move downwardly into engagement with the plunger head 30. The rod 47 is held substantially centrally or axially of the reservoir 14 by means of a plurality of radially arranged veins or guide members 49 and 50. The guide members 49 and 50 are disposed in spaced-apart relation

with respect to each other and positioned closely adjacent the opposite ends of the rod 47. In practice there are three of these guide members 49 and 50 which are adapted to loosely or slidably engage the inner surface of the reservoir 14 and thereby hold the operator 47 concentrically of the reservoir or handle 14.

In the use and operation of this lubricator the handle 14 is filled with a suitable lubricating or cutting fluid by removing the filler plug 15 and inserting the fluid into the handle or reservoir 14 from the outer or upper end thereof. The spring 31, about the plunger 24, is of such strength that it will normally hold the plunger 24 in an inoperative position which is the position shown in Figure 2. When the reservoir 14 is filled the fluid will flow past the plunger 24 along the flat surface 28 thereof, and into the fluid ejecting chamber 29. When the handle 14 is rotated and assumes a substantially vertical position, the plunger operator 46 will drop downwardly until it strikes the head 30. At this time the plunger 24 will be given an inward movement which will force the liquid in the chamber 29 past the valve 33. The force of the liquid moved by the plunger 24 will unseat the valve 33 so that the liquid will flow past the valve 33 and into the liquid conducting member 45. The conducting member 45 will conduct the liquid to the desired point with respect to the work 12.

In this manner the plunger or ejector 24 will be moved to a fluid ejecting position at each revolution of the die stock 10 so that the work 12 will have a small quantity of lubricant or cutting fluid forced thereonto at each revolution of the die stock 10 and the handle or reservoir 14. In practice, the reservoir or handle 14 may be of the same size as the handle 13, being formed of a short length of pipe similar to the tubular or hollow handles at present in use on die stocks of this type.

By providing a fluid ejecting means as hereinbefore described, the fluid will not leak out of the reservoir 14 if the handle or reservoir 14 is left in a vertical position as after the initial impact of the operator 46 with the plunger head 30 the spring 31 will return the plunger 24 to an innermost position and relieve the valve member 33 from any fluid pressure so that the spring 40 may hold the valve member 33 in a closed position.

The provision of the spring 31 about the plunger 24 serves not only as a means for returning the plunger 24 to its inoperative position, but also as a means for forming a partial vacuum in the fluid ejecting chamber 29 so that the fluid in the reservoir 14 will be drawn into the chamber 29 along the flat surface 25 of the plunger 24.

While the lubricator heretofore described has been shown applied to a threading stock and die structure, this lubricator may also form a part of a pipe cutter. Where desired or considered necessary two or more handles may be formed with this lubricator, it being understood that the showing of only one handle as a lubricator is merely an illustration of the application of one of such devices to a stock and die structure.

What I claim is:

1. In a stock and die structure including a pair of radial operating handles, one of said handles being hollow and constituting a fluid reservoir, a valved body in the inner end of said one handle, said body including a normally closed spring-pressed valve, a fluid receiving chamber in said

body inwardly of said valve, a plunger slidably carried by said body and movable into said chamber for ejecting the fluid therefrom, said plunger having a flat longitudinal face coacting with the wall of said chamber for providing a fluid passage communicating with said reservoir and said chamber, spring means normally urging said plunger outwardly of said chamber with a portion of said plunger projecting into said reservoir, said plunger also having a peripheral cutout, a threaded member carried by said body and engaging in said cutout to thereby limit the movement of said plunger under the action of said spring means, and gravity operated means slidable in said reservoir and engageable with said plunger to move said plunger inwardly of said chamber when said one handle is in a substantially vertical upper position for forcing a quantity of fluid past said valve.

2. In a stock and die structure including a pair of radial operating handles, one of said handles being hollow and constituting a fluid reservoir, a valved body in the inner end of said one handle, said body including a normally closed spring-pressed valve, a fluid receiving chamber in said body inwardly of said valve, a plunger slidably carried by said body and movable into said chamber for ejecting the fluid therefrom, said plunger having a flat longitudinal face coacting with the wall of said chamber for providing a fluid passage communicating with said reservoir and said chamber, spring means normally urging said plunger outwardly of said chamber with a portion of said plunger projecting into said reservoir, said plunger also having a peripheral cutout, a threaded member carried by said body and engaging in said cutout to thereby limit the movement of said plunger under the action of said spring means, a plunger operating rod loose in said one handle, and means fixedly carried by said rod slidably engageable with the inner surface of said one handle for holding said rod coaxial with said one handle, said rod moving downwardly to a plunger engaging position when said one handle is in a substantially vertically disposed uppermost position for forcing a quantity of fluid past said valve.

3. In a stock and die structure including a pair of radial operating handles, one of said handles being hollow and constituting a fluid reservoir, a filling plug in the outer end of said one handle, a valved body in the inner end of said one handle including an outwardly closing spring-pressed valve, a fluid receiving chamber carried by said body, a plunger slidable in said chamber and projecting from said body into said reservoir, an impact head carried by said plunger and disposed in said reservoir, a spring about said plunger engaging said body and said head for urging said plunger outwardly of said chamber, said plunger having a flat longitudinal face coacting with the wall of said chamber for providing a fluid passage communicating with said reservoir and said chamber, said plunger also having a peripheral cutout, a threaded member carried by said body and engaging in said cutout to thereby limit the movement of said plunger

under the action of said spring, and a plunger operator slidable in said reservoir and engageable with said head when said one handle is in a substantially vertical upper position to thereby force said plunger inwardly of said chamber and eject the fluid in the latter past said valve.

4. In a stock and die structure including a pair of radial operating handles, one of said handles being hollow and constituting a fluid reservoir, 10 a filling plug in the outer end of said one handle, a valved body in the inner end of said one handle including an outwardly closing spring-pressed valve, a fluid receiving chamber carried by said body, a plunger slidable in said chamber and projecting from said body into said reservoir, an impact head carried by said plunger and disposed in said reservoir, a spring about said plunger engaging said body and said head for urging said plunger outwardly of said chamber, said plunger having a flat longitudinal face coacting with the wall of said chamber for providing a fluid passage communicating with said reservoir and said chamber, said plunger also having a peripheral cutout, a threaded member carried by said body 20 and engaging in said cutout to thereby limit the movement of said plunger under the action of said spring, a plunger operator slidable in said reservoir and engageable with said head when said one handle is in a substantially vertical upper position to thereby force said plunger inwardly of said chamber and eject the fluid in the latter past said valve, and tubular fluid conducting means connected with said body for conducting the fluid to the work.
5. As a new article of manufacture, a combined stock die handle and work lubricator structure, said structure comprising a tubular member constituting a die handle and a fluid reservoir, a filler plug at the outer end of said member, means at the inner end of said member for attaching the latter to the stock, a valved body carried by the inner end of said member including a fluid receiving chamber, a fluid conducting-off means leading from said chamber, an inwardly opening normally closed spring pressed lengthwise slidable valve interposed in said means and a spring controlled plunger slidable in said chamber and having a portion extending into said reservoir, said plunger being formed lengthwise 40 of its periphery with a flat facet and circumferentially of its periphery with a cutout intersecting said facet intermediate the ends of the latter, said facet coacting with the wall of said chamber for providing a fluid conducting passage communicating with said reservoir and chamber, means carried by said body and coacting with said cutout for limiting the extent of the movement of said plunger due to the action of the plunger's controlling spring, and a gravity operated plunger operator slidable in said reservoir 50 and engageable with said portion of said plunger for operating the latter when said member is in a substantially vertical position with said plug uppermost to thereby provide for ejecting fluid past said valve into the fluid conducting-off means.
